Munro & Leo.
ATTORNEY

UNITED STATES PATENT OFFICE

SAMUEL T. YOUNG, OF MIAMI, FLORIDA

GOLF PLAYING DEVICE

Application filed August 6, 1930. Serial No. 473,423.

5 My invention relates to improvements in devices for playing golf, and is designed to be used particularly in connection with miniature golf courses, although it may be used in and of itself as a golf game, and it consists in the combinations, constructions and arrangements herein described and claimed.

10 An object of my invention is to provide a device into which a ball may be driven by an ordinary golf club, and which is divided into a number of different compartments into any one of which the ball may drop.

15 A further object is to provide a device of the type mentioned in which a visible signal is actuated to indicate the compartment into which the ball has dropped.

20 A further object is to provide a device in which the signal, after indicating the particular compartment, is reset automatically.

25 A further object of the invention is to provide a device of the type described which may be used in connection with a miniature golf course to intensify interest in the game by means of additional hazards or features of chance, as well as to provide a device which might be used by itself since the elements of chance are provided therein, and this will insure interest in the game when the device is used alone.

30 Other objects and advantages will appear in the following specification and the novel features of the invention will be particularly pointed out in the appended claims.

35 My invention is illustrated in the accompanying drawings forming a part of this application, in which:

Figure 1 is a perspective view of the device arranged for playing.

40 Figure 2 is an enlarged vertical sectional view through the device.

Figure 3 is a section along the line 3—3 of Fig. 2, and,

45 Figure 4 is a section along the line 4—4 of Fig. 3, certain supporting members being removed to show the construction beneath.

In carrying out my invention I provide a receptacle which in the present instance has the form of a keg 1. This keg is preferably 50 provided with a hinged top 2 having a bail

or handle 3 by which the top may be raised and the top has a hasp 4 arranged to receive an eye 5 to which a lock 6 may be attached so as to lock the top in position when desired. The bottom 7 of the keg is preferably inclined 55 toward a central opening 8. A pipe 9 projects into this opening and is disposed in a wood base 10, the pipe 9 forming a pivot member about which the receptacle 1 may be turned. While I have shown the bottom 7 as 60 being in the ordinary form of a keg bottom, a metal bottom might be provided so as to cause a noise when the ball hits the bottom.

Disposed on the interior of the receptacle 1 are four brackets or supporting members 65 such as those shown at 11. Each of these brackets bears a post or upright 12 to which is pivotally secured an arm 13 having at one end a flag 14 and being pivotally attached at the other end to a downwardly extending rod 15. 70 The latter is secured at the point 16 to a double wire terminal which is curved inwardly as shown at 17. The arms 13 extend laterally through slots 18 in the receptacle 1. In the present instance I have shown four of the 75 arms which correspond to four compartments hereinafter described, but it is obvious that any suitable number might be provided without departing from the spirit of the invention.

Below the supporting members 11 is a partition 19, this partition being provided with openings 20 corresponding to compartments formed in the present instance by heart-shaped metal receptacles 21. The receptacles 21 have openings 22^a therein registering with the openings 20. Disposed centrally of the partition 19 is a post having a rounded head 22. Arranged to extend through an opening in the side of the receptacle 1 is a pipe 23, which, as will be observed, is inclined upwardly. This pipe terminates in a rounded portion 23^a having a funnel shaped flange 23^b arranged to form a central opening 23^c, the center of this opening being in axial alignment with the center of the rounded post head 22. The pipe 23 communicates with a pipe 24 which terminates at its forward end in a flared portion having a rectangular opening 25 communicating with a box-like member 100

26, see Figure 1. The box 26 has an open side facing a tee. The latter consists preferably of a circular wooden block 27, which has a small fiber brush 28 inserted in the center thereof, allowed to extend a little bit above the surface of the block, thus holding the ball free from the block and affording a better opportunity for the player to hit the ball accurately.

10 From the foregoing description of the various parts of the device the operation thereof may be readily understood. The device on its base 10, may be disposed in a wall area 29 such as that shown in Fig. 1 on a miniature golf course, and may constitute or take the place of one of the holes to be negotiated in said miniature golf course. In Fig. 1 I have indicated this hole as number 18. The player places the ball on the tee 28 and drives 20 the ball into the box 26, attempting to direct it into the pipe 24, and thence through the pipe 23. The ball will hit the end of the pipe 23^a and will then drop through the opening 23^c on to the head 22. From thence 25 it will pass into one of the receptacles 21, and will drop through the aligned openings 22 and 20 on to the curved portion 17 of one of the signalling devices. The weight of the ball will cause a downward movement of the portion 17, the rod 15, and will cause the arm 13, together with its flag to be raised, thus indicating to the player which compartment the ball dropped into. The ball will roll off from the curved portion 17 and 30 will pass through the openings 8 and the pipe 9.

In the present illustration I have shown an underground pipe 30 leading to ball receiver 31, from which the balls may be received. In order that a greater element of chance may be injected into the game, the pipe 23 where it joins with pipe 24, is angularly inclined with respect to the latter, so that in driving the ball into the pipe 24 45 if the stroke is too hard the ball will bounce back and roll to the mat or tee, and if the stroke is too light the ball will fail to reach the point where it would drop through the hole 23^c.

50 The compartment 21 may have different values and in a miniature golf game the player may be credited with a certain number of strokes, depending upon the particular compartment into which the ball fell.

55 The device may be used by itself and in such a case the ball may be discharged from the bottom of the device into a basket or other suitable receiver and the compartments may have values which entitle participants to certain prizes which may be indicated by attaching tags, not shown, adjacent to the flags.

As a protection to the flags I may provide the laterally extending horse-shoe shaped guard member 32, which not only serves as 60 a protection to the flag, but also symbolizes

good luck and adds to the appearance of the device.

I claim:

1. A golf playing device comprising a receptacle, compartments disposed in the receptacle, a pipe leading into the receptacle and being arranged to deliver a ball and a centrally disposed post having a rounded head disposed beneath the end of the pipe for receiving the ball directing it into the compartments, and a visible signal associated with each of said compartments and arranged to be actuated mechanically by the ball subsequent to the entrance of the ball into one of said compartments. 70

2. A golf playing device comprising a receptacle, compartments disposed in the receptacle, a pipe leading into the receptacle and being arranged to deliver a ball and a centrally disposed post having a rounded head disposed beneath the end of the pipe for receiving the ball directing it into the compartments, each of said compartments having an opening in the bottom thereof, a visible signal associated with each of said compartments and a signal operating member arranged to be engaged by the ball after its passage from the compartment for actuating the signal to indicate the compartment into which the ball has dropped. 75

3. A golf playing device comprising a receptacle, a plurality of compartments disposed therein, a pipe leading into the receptacle and having a horizontally disposed opening at its end, a post having a rounded head disposed beneath said opening for directing a ball delivered through the opening into any of said compartments, each of said compartments having an opening in the bottom thereof, a curved member disposed below the opening in each compartment arranged to be engaged by the ball, a pivoted arm arranged to extend through the side of the receptacle and having connection with said curved member whereby the arm may be moved when the ball engages the curved member. 100

4. A golf playing device comprising a receptacle having a plurality of compartments therein, a pivoted arm extending through the side of the receptacle and associated with each of said compartments, a downwardly extending link connected to each pivoted arm and having a curved portion extending underneath the bottom of its individual compartment, each of said compartments being provided with an opening immediately above said curved portion, and a visible signalling device attached to the arms on the exterior of the receptacle. 115

5. In a golf playing device, a receptacle having a plurality of compartments, each of said compartments having an opening in the bottom thereof, a curved member disposed below the opening in each compartment ar- 120

ranged to be engaged by the ball, a pivoted arm arranged to extend through the side of the receptacle and having connection with said curved member whereby the arm may be moved when the ball engages the curved member.

6. A golf playing device comprising a receptacle, a plurality of ball receiving compartments disposed within said receptacle, each of said compartments having an opening in its bottom, a support disposed above said compartments, a bracket carried by said support above each compartment, an arm pivoted on each of said brackets, each of said arms extending exteriorly of the receptacle and bearing a visible signal, a rod pivotally connected to the inner end of each of said arms, and having a portion extending underneath the opening of its individual receptacle whereby the arm is moved by the engagement of a ball with said portion.
